JEWELLED GARMENT SUPPORT

Everell S. Van Tassel, Erie, Pa.

Application April 6, 1955, Serial No. 35,388

Term of patent 14 years

(Cl. D17—3)

FIG. 1

Fig. 1 is a perspective view of a jeweled garment support showing my new design;

Fig. 2 is an enlarged front view of the attaching means; and

Fig. 3 is an enlarged rear view of the attaching means.

I claim:

The ornamental design for a jeweled garment support, as shown.
